US00D492215S1

(12) **United States Design Patent** (10) Patent No.: **US D492,215 S**
Lu (45) Date of Patent: **** Jun. 29, 2004**

(54) **ELECTRONIC ARTICLE SURVEILLANCE DEVICE**

(75) Inventor: **Nan Lu, Hangzhou (CN)**

(73) Assignee: **Universal Surveillance Corporation, Rancho Cucamonga, CA (US)**

(**) Term: **14 Years**

(21) Appl. No.: **29/182,920**

(22) Filed: **Jun. 2, 2003**

(51) LOC (7) Cl. **10-05**

(52) U.S. Cl. **D10/104; D10/106**

(58) Field of Search **D10/104, 106, D10/116; 340/571, 572.7-572.9, 573.4; 70/57.1; 24/704.1**

(57) **CLAIM**

The ornamental design for an electronic article surveillance device, as shown and described.

DESCRIPTION

FIG. 1 is a side perspective view of the electronic article surveillance device in an unengaged state;
 FIG. 2 is a side perspective view of the electronic article surveillance device in an engaged state;
 FIG. 3 is a left hand side view of the electronic article surveillance device in an unengaged state;
 FIG. 4 is a right hand side view of the electronic article surveillance device in an unengaged state;
 FIG. 5 is a top view of the electronic article surveillance device in an unengaged state;
 FIG. 6 is a bottom view of the electronic article surveillance device in an unengaged state;
 FIG. 7 is a frontal view of the electronic article surveillance device in an unengaged state; and,
 FIG. 8 is a rear view of the electronic article surveillance device in an unengaged state.
